(57) **CLAIM**

The ornamental design for an apparatus for docking and charging electrophoresis devices, as shown and described.

DESCRIPTION

FIG. 1 is a front and side perspective view of an apparatus for docketing and charging electrophoresis devices according to our design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a front and side perspective view of an apparatus for docking and charging electrophoresis devices according to a second embodiment;

FIG. 8 is a front view thereof;

FIG. 9 is a back view thereof;

FIG. 10 is a right side view thereof;

FIG. 11 is a left side view thereof; and,

FIG. 12 is a top view thereof.

A new ornamental design for an apparatus for docking and charging electrophoresis devices for performing electrophoresis of nucleic acids, and visualization, imaging and/or analysis thereof, at locations where there may not be direct electrical power supply.
